COMMUTATOR

Raymond G. McCusker, Lowell, Mass., assignor to
 Heinze Electric Corporation, Lowell, Mass., a
 corporation of Michigan

Application July 5, 1940, Serial No. 344,043

11 Claims. (Cl. 171—321)

The present invention relates to commutators of dynamos and to a method of making the same.

It is an important object of this invention to provide a novel construction in a commutator for small motors and the like whereby such commutators may be inexpensively formed to provide a rigid structure adequate to meet the conditions imposed by temperature, voltage, and centrifugal force in small dynamos.

It is also an important object of this invention to provide a novel method of making commutators for small motors and the like.

Other and further important objects of this invention will be apparent from the disclosures in the specification and the accompanying drawing, in which:

Figure 1 is a plan view of a strip of metal to be bent and cut to define a commutator for dynamos;

Figure 2 is a top view showing of the strip of Figure 1 bent to define a cylinder;

Figure 3 is a sectional side view of the cylinder of Figure 2 along lines II—II;

Figure 4 is a side view of a commutator formed from the strip of Figure 1;

Figure 5 is a sectional view of the commutator of Figure 4;

Figures 6, 7, and 8 are plan views of strips of metal to show modifications in the slot shape;

Figure 9 is a view in elevation of a metal strip bent into a cylinder and showing a modification in slot shape;

Figure 10 is a view in elevation of the cylinder of Figure 9 filled with a plastic and shaped to define a commutator; and

Figure 11 is a sectional view of the commutator of Figure 10.

In one form of commutator made according to this invention, a strip of metal, indicated generally by the numerals 10, is shaped to provide a body portion 11, from which there extends longitudinally spaced soldering lugs 12 and longitudinally spaced fingers 14. The strip is apertured, as indicated at 13, the center of the apertures or holes being substantially in line with the upper edge of the body portion (see Figure 1).

The strip 10 is bent so that its body portion defines a cylinder 15 with outwardly bent lugs 12, and with the fingers 14 bent inwardly to define hooks 16, as shown in Figures 2 and 3. A length of fish line 17 is wrapped about the upper end of the cylinder and crossing the apertures, as best indicated in Figure 9, so that a plastic

insulating material forced under high pressure into the mold of Figure 2 will emerge through the apertures 13 and envelop the fish line 17, as indicated at 21 in Figures 5 and 6.

5 Similar numerals indicate similar parts in the figures.

After the strip 10 has been formed into the cylindrical form of Figure 2, the cylinder is placed in a suitable support, a mandrel is placed 10 in the center of the cylinder, plastic insulating material 18 is forced under high pressure into the cylinder, and the mandrel is withdrawn to define the bore for the armature shaft as indicated at 29 in Figure 5. The plastic material is squeezed through the apertures 13 to envelop the fish line 17 and form an external bead 21, and this plastic material extends above the body portion of the strip and, with the bead, forms a substantially T-shaped bead at one end of the 15 commutator as indicated at 19 in Figure 4. The shape of the containing support for the filling operation is such that there is a layer of plastic at the bottom of the commutator at the end of the filling operation, and this is indicated at 29 in Figure 4.

It will now be evident that at the end of the filling operation we have an assembly which presents a body portion surmounted by a cap 19 of the plastic integral with the bead 21, and a bottom layer 20 of plastic, and with the hooks 16 firmly embedded in the plastic. The next operation is that of milling or sawing the body portion of the strip to now define a cylindrical commutator of a plurality of peripherally spaced segments 22, separated from each other in insulated relation to each other by slots 23, and each having its soldering lug 12 to which the leads of armature coils may be soldered.

Figures 1 to 5, inclusive, show the evolution of the commutator from the blank or strip of Figure 1 to the finished cylindrical commutator shown in section in Figure 5.

The contour of the cap portion of the commutator, which includes the bead, and the shape 45 of the lock formed between the plastic and the lug end of the commutator segment may be modified.

In Figure 6 there is shown a portion of a strip 10 with its body portion 11, its fingers 14, and its soldering lugs 12. Slots 24 begin in the body portion 11 and extend into the soldering lugs 12, with substantially half of the length of the slot being in the body portion.

50 In another modification, shown in Figure 7, slots 25 begin in the body portion 11 and ex-

tend into the soldering lugs 12, with the greater portion of the slot being in the lug.

In another modification, shown in Figure 8, triangular openings 26 are formed in the soldering lugs 12 and with the base of the triangle being disposed slightly below the upper edge of the body portion 11.

In another modification, shown in Figures 9, 10, and 11, the soldering lugs 12 are provided with relatively wide and deep slots 27 so that a lead wire 28, as indicated in Figure 10, may be entered in the slot and be bent for soldering to the lugs. A portion of the slot opening appears above the plastic as shown in Figures 10 and 11. The slots begin in the body portion as indicated at 30 in Figure 9, and the major portion of the slot is in the lug 12.

The steps of bending the strip to cylindrical form, filling this cylinder with an insulating material of a plastic which flows outwardly of the strip to form an external bead, and then sawing the strip to provide a cylindrical commutator of peripherally spaced segments, are common to all forms of the strip, so that each segment has its soldering lug at one end and its embedded finger at the other end.

The fish line 17 is a string of strong, fibrous material, and provides an inexpensive and easily applied reinforcing element extending longitudinally of the bead 21. Other materials may be used to provide the longitudinally extending reinforcing element, but fish line has been proved useful because inexpensive, and because the hot plastic finds its way about the strands of the string during the molding operation.

The bead is usually severed during the cutting operation to define the segments because the cutting saw runs through the bead as it finishes its cutting stroke to separate the segments in forming the slot 23.

While I have shown several embodiments of my invention, it will, of course, be understood that I do not wish to be limited thereto, since many modifications may be made, and I therefore contemplate by the appended claims to cover all such modifications as fall within the true spirit and scope of my invention.

I claim as my invention:

1. A commutator assembly formed of a plurality of peripherally spaced commutator segments held in assembled relation to each other by a molded body of insulating material, each of said segments comprising a body portion having an inturned finger at one end embedded in said insulating material and an outturned finger at the other end, said insulating material extending into engagement with opposed surfaces of said outturned finger, thereby to hold said segment firmly in place on said molded body of insulating material.

2. A commutator assembly formed of a plurality of peripherally spaced commutator segments held in assembled relation to each other by a molded body of insulating material, each of said segments comprising a body portion having an inturned finger at one end embedded in said insulating material and an outturned finger at the other end, said outturned finger having an opening therethrough, said insulating material extending through said opening in said outturned finger and into binding engagement with the outer surface of said outturned finger.

3. A commutator assembly formed of a plurality of peripherally spaced commutator segments held in assembled relation to each other

by a molded body of insulating material, each of said segments comprising a body portion having an inturned finger at one end embedded in said insulating material and an outturned finger at the other end having an opening therethrough, said insulating material having an integral T-head lock extending through the opening in said outturned finger, with the T-head portion of said lock on the opposite side of said outturned finger from the main body portion of said insulating material.

4. A commutator formed of a strip of metal shaped to define an elongated body portion, longitudinally spaced and outstanding soldering lugs along one longitudinal margin of the body, and longitudinally spaced and outstanding bent fingers along an opposite margin of the body, means defining apertures in said soldering lugs and extending into said body portion, said strip being bent to define a cylinder having inwardly bent fingers, a filling of an insulating plastic in said cylinder and extending outwardly through the apertures to form an integrally united assembly, said body portion of said cylindrically formed strip being cut to define a plurality of peripherally spaced commutator segments in insulated relation to each other and with each segment having a soldering lug and an embedded finger.

5. A commutator assembly formed of a plurality of peripherally spaced commutator segments held in assembled relation to each other by a molded body of insulating plastic, each of said segments comprising a body portion having an apertured soldering lug at one end and having an inwardly bent finger at the other end with the finger embedded in said body of plastic and an outwardly extending head of said plastic about said assembly and having connecting portions extending through said apertures to integrally connect said head with said body of plastic.

6. A commutator assembly formed of a plurality of peripherally spaced commutator segments held in assembled relation to each other by a molded body of insulating plastic to define a cylinder having an internal filling of the plastic, each of said segments comprising a body portion having an apertured soldering lug at one end and having an inwardly bent finger at the other end with the finger embedded in the plastic filling, said filling being arranged extending through said apertures to define an outstanding bead, and a longitudinally extending reinforcement of fibrous material disposed in said bead.

7. A commutator assembly formed of a plurality of peripherally spaced commutator segments held in assembled relation to each other by a molded body of insulating plastic to define a cylinder having an internal filling of the plastic, each of said segments comprising a body portion having an apertured soldering lug at one end and having an inwardly bent finger at the other end with the finger embedded in the plastic filling, said filling being arranged extending internally above the body portion of the segment and externally through the apertures in said lugs to define a substantially T-shaped bead of plastic.

8. A commutator assembly formed of a plurality of peripherally spaced commutator segments held in assembled relation to each other by a molded body of insulating plastic to define a cylinder having an internal filling of the plastic, each of said segments comprising a body portion having an apertured soldering lug at one

end and having an inwardly bent finger at the other end with the finger embedded in the plastic filling, an externally disposed reinforcing element wrapped about said assembly and crossing said apertures, said filling being arranged extending through said apertures and about said reinforcing element to provide an external bead.

9. A commutator assembly formed of a plurality of peripherally spaced commutator segments held in assembled relation to each other by a molded body of insulating plastic to define a cylinder having an internal filling of the plastic, each of said segments comprising a body portion having a bent finger at one end with the finger embedded in the plastic, and having a soldering lug at the other end provided with a slot extending into the body portion, an externally disposed reinforcing element disposed about said assembly and crossing said slots, said filling being arranged extending through said slots and about said reinforcing element to provide an external bead.

10. A commutator assembly formed of a plu-

rality of peripherally spaced commutator segments held in assembled relation to each other by a molded body of insulating plastic to define a cylinder having an internal filling of the plastic, each of said segments comprising a body portion having an inwardly bent finger at the other end with the finger embedded in the plastic, an externally disposed reinforcing element disposed about said assembly and adjacent the one end of the segment, said filling being arranged extending outwardly of said segments and about said reinforcing element to provide an external bead.

11. In combination, a central body of an insulating plastic, a plurality of peripherally spaced segments disposed about said central body to define a commutator, means on said segments embedded in said central body, elongated beads of insulating plastic engaging the external faces of said segments and formed integral with said central body, and longitudinally extending reinforcing means in said beads.

RAYMOND G. McCUSKER.
